UNITED STATES PATENT OFFICE.

JOHN SONTHEIMER, OF LINCOLN, NEBRASKA.

TELEPHONE-DIRECTORY

1,054,465.

Specification of Letters Patent. Patented Feb. 25, 1913.

Application filed September 10, 1912. Serial No. 719,510.

To all whom it may concern:

Be it known that I, JOHN SONTHEIMER, a citizen of the United States, and a resident of Lincoln, in the county of Lancaster and 5 State of Nebraska, have invented a new and Improved Telephone-Directory, of which the following is a full, clear, and exact description.

This invention relates to telephone directories, and has reference more particularly 10 to a device of this class which comprises a plurality of circular members carrying reference characters and provided with means whereby any desired reference is rapidly 15 found.

An object of the invention is to provide an inexpensive and compact telephone directory, simple and durable in its construction, and which can be easily attached to a telephone and will not interfere with its action 20 or add much to its bulk.

Another object of the invention is to provide a telephone directory carrying telephone references and addresses of such 25 parties with whom most of the telephone connections are made, and to locate such references when desired with a minimum expenditure of time.

A further object of the invention is to 30 provide a device to which telephone references may be easily added or replaced, the addition of the reference not requiring any change in the structure of the device.

Reference is to be had to the accompanying 35 drawings forming a part of this specification, in which like characters of reference indicate corresponding parts in all the views, and in which—

Figure 1 is a face elevation of an embodiment of my invention partly broken away to expose one of the reference disks, the dotted position of the disk showing the position when looking for a desired telephone number; Fig. 2 is a part of the device in 45 section taken on the line 2—2 in Fig. 1; Fig. 3 is an enlarged perspective view of a part of the reference carrier; Fig. 4 is a perspective view of the roller with the loop member; and Fig. 5 is a perspective view 50 of the telephone provided with my device.

Before proceeding to a more detailed description of my invention it must be under-

stood that the drawings submitted show only a special type of a telephone and that my device may be attached to any form of 55 a telephone by a corresponding modification of the means of attachment of my device. The reference carriers may be circular or of any other shape, and, similarly, the casing for said disks.

Referring to the drawings, 10 is a casing 60 preferably cylindrical in shape, having its ends formed by means of circular end walls 11 and 12 and its lateral surface 13 only semi-circular; thus an opening is left in the 65 casing on its lateral surface between the end walls 11 and 12. Loosely fitted in said casing is a plurality of circular disks 14 provided with an engaging edge ring 15 straddling the edge of the disk 14, the diameter 70 of said ring being a little less than the interior diameter of the casing 10. The disk 14 is provided on one of its faces with a circular piece of paper having the proper 75 references printed or otherwise provided on this paper. The paper may be secured to the disk by pasting same on the disk, or clamping means may be provided on the disk for maintaining the paper on same. The ring 15 is provided with a flange 16 projecting 80 above the lateral surface of the casing 10, and is provided with a letter stamped in said flange, or otherwise secured to same, and indicating the name of the party whose name begins with the same initial.

The disks 14 provided with the rings 15 85 are interposed by means of small circular disks 17 so that the rings 15 bear easily with their sides against the face of the disk 17. The purpose of the smaller disks 17 is 90 to prevent interference between any pair of consecutive rings 15. The so-formed alternate series of circular disks 14 and 17 are eccentrically mounted on a pin 18 rigidly fixed in the walls 11 and 12 of the 95 casing 10 near its lateral surface and projecting out of the sides. The edges of the disks 14 and 17 are normally at the same level with respect to the lateral surface of the casing 10. The disks 14 being eccentrically mounted near the lateral surface of the casing 10 when swung on the pin 18 out 100 of the casing will expose the maximum of their face carrying the references, while the

disks 17, being fixed on the pin 18, will not be displaced. The projecting pin 18 at one of its ends carries a wire coil spring 19 having one of its ends fixed on the end wall 11; 5 the other end of the said spring 19 forms a loop member 20 about the lateral surface of the casing and resting on the other end of the projecting pin 18. The part of the loop 20 parallel to the lateral surface of 10 the casing 10 is provided with a rubber roller 21. The loop 20 and roller 21, by means of the coil spring 19, are continuously forced toward the lateral surface of the casing 10. The casing 10 is also provided 15 with a split ring 22 having two end flanges 23 formed in the split and adapted to receive a bolt 24. The ring 22 is also provided with a projecting portion 25 in line with the lateral surface of the ring and riveted 20 or otherwise secured to the wall 12 of the casing 10. By means of the split ring 22 the device is placed on the body of the telephone 28 and clamped to same by the medium of the bolt 24 (see Figs. 1 and 5). The lateral 25 surface of the casing 10 is also provided with a hooked member 26 adapted to receive the paper 27 to be used for memorandum when necessary.

My device, as shown in Fig. 5, is placed 30 so as to have the indicating flange 16 provided with the letters of the alphabet to face the person using the telephone. When a number is to be called the initial of the name of said party being found on the indicator 35 flange, by forcing this flange to the left (Fig. 1) the face of the disk 14 carrying the papers with the printed names, telephone number and address, is exposed and can be readily seen and the desired party's name is 40 easily found, as shown in dotted lines in Fig. 1. By the outward movement of the disk 14 the rubber roller 21 is also forced away from the lateral surface of the casing 10 and thereby increases the tension of the 45 winding of the coil spring 19 so that when the finger holding the indicating flange 16 is released the spring 19 forces the disk 14 to its original position by means of the roller 21, as can be easily seen from the drawings. 50 It is readily seen that with my device the expenditure of time required to find the numbers of the parties with whom most of the telephone connections are made is diminished to a minimum; the reference being attached to the telephone itself cannot be mislaid, and any desired additional reference 55 can be easily made either by printing directly on the paper fixed to the disk 14 or by pasting or otherwise securing a new paper 60 disk on the disk 14.

Having thus described my invention, what I claim as new and desire to secure by Letters Patent is:—

1. A device of the class described comprising

ing a cylindrical casing formed by circular 65 end walls and a semicircular lateral surface inclosed between said walls whereby an opening is formed in the lateral surface of said casing between said end walls, said lateral surface being provided with means for carrying paper, a pin in said casing projecting through said end walls and near the opening in the lateral surface, a plurality of disks adapted to carry reference characters and eccentrically mounted on said pin, said 70 disks having rings straddling their edges and provided with an identification member for said reference characters, said rings and disks adapted to be swung out of said casing through said opening, a plurality of smaller 75 disks also eccentrically mounted on said pin intermediate said rings and bearing against and fixed on said pin, a coil spring positioned on one of the projecting ends of said pin having one of its ends attached to the 80 end wall of said casing and the other end forming a loop about the lateral surface of said casing and resting on the other projecting end of said pin, a rubber roller positioned on said loop and bearing against said 85 straddling rings and normally keeping said rings and disks in said casing, and clamping means associated with said casing for the 90 purposes above described.

2. A device of the class described comprising 95 a cylindrical casing having a lateral opening and series of circular disks; a pin in said casing projecting out of the end of same, said series of disks being eccentrically mounted on said pin and said casing, each 100 of the series of said disks being adapted to carry reference characters and having means for identification of said reference characters projecting out of said casing; a resilient member associated with the projecting end 105 of said pin, the casing and the disks carrying the reference characters whereby said disks are normally maintained in said casing; and circular clamping means axially associated with said casing and attached to same for 110 the purpose substantially as described.

3. A device of the class described comprising 115 a cylindrical casing formed by circular end walls and a semicircular lateral surface inclosed between said walls whereby an opening is formed in the lateral surface of said casing between said end walls; a pin in said casing projecting through said end walls and near the opening in the lateral surface; a plurality of disks adapted to carry reference characters and eccentrically mounted on said pin, said disks adapted to be swung out of said casing through said opening; a plurality of spacing members mounted on said pin intermediate said disks and fixed on said 120 pin; a spring positioned on one of the projecting ends of said pin, having one of these ends attached to the end wall of said casing 125

and the other end forming a loop about the lateral surface of said casing and resting on the other projecting end of said pin, and a roller positioned on said loop and bearing 5 against said disks for normally keeping same in said casing.

In testimony whereof I have signed my

name to this specification in the presence of two subscribing witnesses.

JOHN SONTHEIMER.
